SAFETY DEVICE FOR ELEVATORS

James Dunlop, Ridgewood, N. J., and Hans E. Hansen, Westerly, Staten Island, N. Y., assignors, by mesne assignments, to Westinghouse Electric Corporation, East Pittsburgh, Pa., a corporation of Pennsylvania

Application December 6, 1943, Serial No. 513,030

21 Claims. (Cl. 187—83)

1

Our invention relates to safety devices for elevators and, more particularly, to friction safety devices for large deck-edge elevators on ships, or for drawbridges or heavy freight elevators.

One object of our invention is to provide a safety apparatus for an elevator body with two sets of hoisting cables which will provide means for stopping both ends of the elevator body in either the up or the down direction when either set of cables breaks.

Another object is to provide a friction safety apparatus for each end of an elevator platform having two sets of hoisting cables in which the frictional resistance to the falling end of the platform in case of a break in the cables will be different from the frictional resistance in the safety apparatus at the other end of the platform if it moves upwardly.

A further object is to provide a safety device for an elevator having safety pawls on the elevator platform for engaging notches in the elevator guide and for positioning the pawls at a pitch which is a multiple of the pitch of the notches on the elevator guides so as to reduce the distance of free fall of the elevator platform in case of a break in its cables.

A still further object is to provide a pawl and notch operated safety device for an elevator body having a set of hoisting cables at each end in which all of the pawls will be operated at the same instant to stop the elevator body regardless of which set of cables fails.

A still further object is to provide a safety apparatus for an elevator platform having a set of hoisting cables at each end attached to hitch boxes having hitch plates for operating the safety apparatus, and in which box springs are compressed by the tension of the cables to store energy for shooting the hitch plates out of safe position into safety operating position when the safety is operated by the failure of one or both sets of cables.

A further object is to provide a safety apparatus for exceptionally large elevator bodies which shall be rugged and which will provide sufficient frictional resistance to bring such large bodies to a stop within a very short distance without damaging either the elevator bodies or the apparatus or structures associated with it.

It is also an object of our invention to provide a frictional safety device which shall be simple and easy to manufacture, install, and maintain in operation.

Reference may be had to the accompanying

2

drawings for a better understanding of the invention.

Figure 1 is a diagrammatic representation in aft end elevation of a deck-edge elevator attached to an outboard portion of the hull of a ship;

Fig. 2 is a diagrammatic view of the elevator shown in Fig. 1 as taken from the interior of the ship and looking in outboard direction, for illustrating the hoisting apparatus more clearly;

Fig. 3 is a top plan view of the elevator platform and guide rails with our improved safety apparatus attached thereto;

Fig. 4 is a view in side elevation looking in the outboard direction of the elevator platform, parts of its hoisting cables, and our improved safety apparatus associated therewith;

Fig. 5 is an enlarged view in aft end elevation of our improved safety apparatus shown in Fig. 3 mounted on the aft end of the elevator;

Fig. 6 is an enlarged view in side elevation looking in outboard direction of one of the safety devices shown in Fig. 3 as mounted on the aft end of the elevator;

Fig. 7 is an enlarged view of the energy storing spring, casing and push rod for biasing the safety operating rod into safety releasing operation;

Fig. 8 is a view in side elevation, partly in full line and partly in section, of two of the safety pawls and the friction plates and friction springs associated therewith;

Fig. 9 is a view taken on the line IX—IX of Fig. 8;

Fig. 10 is a view taken on the line X—X of Fig. 9 as seen when looking aft at the safety shown in Fig. 5, and

Fig. 11 is a view in end elevation of a portion of the upper end of the safety devices showing how its outer plate is bolted to its support.

Our invention is illustrated in connection with 40 a deck-edge elevator such as is used on airplane carrier ships for transferring airplanes from the main deck to the flight deck or from the flight deck to the main deck. Elevators of this type have their platforms mounted on the outside of 45 the hull at one side of the ship in alignment with an opening therein to the main deck and are movable up and down on the side of the ship to serve the main deck and the flight deck. Some of these platforms are approximately sixty feet long and 50 extend outwardly from the hull over thirty feet. However, it is to be understood that the invention may be used in connection with many other forms of elevators, drawbridges, etc.

Referring more particularly to Figs. 1 and 2 of 55 the drawings, we have illustrated a deck-edge

elevator comprising an elevator platform 10 disposed between a pair of guide rails 11 and 12 mounted on the outside of a ship hull 13, in position to be supported by and to be raised and lowered between a main deck 14 and a flight deck 15 by a plurality of hoisting cables 16 and 17 operated by a hoisting engine 18.

The platform 10 comprises a base section 20 and a hinged or outboard section 21 which normally lie in the same plane and provide a large 10 level area upon which airplanes may be moved and carried from one deck to the other. The base section of the platform is constructed with a suitable flooring 22 laid upon a frame 23 made of seamless steel tubing, structural steel sections 15 and steel plate welded together in bridge-like construction to form a relatively light but strong body. The outboard section of the platform is also constructed with a suitable floor 24 laid upon a frame 25 of seamless steel tubing, structural steel and steel plate welded together in bridge-like construction in the same manner as the base and is mounted upon and connected to the base with a suitable hinged joint 26 so that it may be raised from its normal horizontal position into a vertical position on the base when the ship has to pass through a lock or other narrow opening.

The guide rails 11 and 12 are mounted in position and facing each other on the side of the ship hull 13 by means of a plurality of horizontally disposed brackets 28.

The guide rails are provided with vertical slots 29 in their sides facing each other for receiving a plurality of rollers 31 rotatably mounted on the base section 20 for the purpose of guiding the movement of the elevator platform as it is raised or lowered and for also maintaining the platform in its horizontal position. A block 32 is securely fastened by welding to the lower end of each guide rail to prevent the elevator from dropping on down through the slots in case of failure of the safeties, cables, etc. Normally the platform is suspended entirely by the hoisting cables. The guide rails are also provided with notched sides 33 so that they may be used as safety standards in cooperation with safety apparatus for stopping the platform in case of failure of the hoisting cables.

The hoisting engine 18 is a hydraulic engine comprising a single cylinder 34 mounted in a horizontal position on a frame or engine bed 35 and a power plunger 33 disposed in the cylinder. The outer end of the plunger is provided with a power head 37 in which a pair of power sheaves 38 are rotatably mounted. The plunger is designed to slide back and forth in the cylinder and thereby move the power sheaves to operate the hoisting cables. Any suitable hydraulic medium such as oil placed under pressure by any suitable pumping apparatus (not shown) may be used for operating the plunger. A valve 40 and a motor 41 for operating it are mounted on the cylinder for controlling the operation of the plunger by controlling the admission of the oil to the cylinder.

The hoisting cables 16 are secured to the aft end of the platform (Fig. 2) by suitable hitches 42 mounted thereon and pass upwardly and over an idler sheave 43 fastened to the ship structure underneath the overhanging portion of the flight deck, thence rearwardly over a second idler sheave 44 mounted on the ship frame inside the hull, thence downwardly and under a deflector sheave 45 mounted on the engine bed 35, thence around a stationary sheave 46 mounted on the 75

engine bed at the rear of the engine, thence around one of the power sheaves 38, and thence to a plurality of hitches 47 mounted on the underside of the engine cylinder.

The hoisting cables 17 are secured to the fore end of the platform by suitable cable-hitches 48 mounted thereon and pass upwardly and over an idler sheave 49 fastened to the ship structure underneath the overhanging portion of the flight deck, thence rearwardly over a second idler sheave 50 mounted on the ship frame inside the hull, and thence downwardly and under a deflector sheave 51 mounted on the fore end of the engine bed, thence under and over one of the power sheaves 38 in the plunger head, and thence to suitable dead-end hitches 52 secured to the upper rear part of the engine.

Inasmuch as the platform 10 is very long and heavy and is operated and supported entirely between its guide rails by the hoisting cables at its fore and aft ends, an ample safety means for stopping it quickly and safely and resting it upon its guide rails, upon failure of the hoisting cables at either or both ends of the platform is required. Furthermore, inasmuch as the platform is operated by two sets of cables, one at each end, a safety means for both up and down direction is required, so that if the cables at one end break and the cables at the other end continue their upward pull, the platform will be stopped at both ends before it tilts to a dangerous position.

Also, in case of failure of the cables at only one end while the platform is moving upwardly, the downward pull of gravity at that end and the upward pull of the intact cables at the other end will require the application of different frictional stopping forces for the up direction and the down direction to keep the platform from being stopped in a tilted condition.

In order to meet these requirements, we have provided the platform with safeties 53 and 54 having stopping pawls biased to engage notches 33 on the guide rails or safety standards to stop the platform upon failure of either or both sets of cables. The pawls on both safeties are restrained from operation by a pair of gates controlled through an operating rod 55 biased towards pawl releasing position by a compression spring 56 in a casing 57 but prevented from moving to its pawl releasing position by trigger hitch plates 58 and 59 on the platform ends of the cables. Furthermore, friction plates are mounted in the safeties to permit a limited relative movement between the safeties and the platform when the safeties grab the guide rails for either direction.

If either set of cables fails, its trigger hitch plate releases the rod to operation by the biasing spring which causes the rod to release the pawls on both safeties so that they dig into the notched guide rails and thereby stop the safeties and the platform, the friction plates absorbing such damaging energy as may be generated by the sudden stopping of the platform by the safeties.

Referring more particularly to Figs. 6, 8, 9, 10 and 11, the safety 53 comprises a pawl carriage or safety device 64 connected by frictional devices with a housing 61 having a rear housing plate 62 and a front housing plate 63 mounted on the platform. The rear housing plate 62 is provided with an inwardly extending friction fin or plate 65 and is mounted in a vertical position between an upper beam 66 and a lower beam 67 constructed of steel plates. Each beam is welded securely to the frame 23 of the base section plat-

form. The rear housing plate 62 is welded to the beams so as to provide a strong permanent attachment to the platform frame sufficient to withstand any strain which may be placed upon the safety. The front housing plate 63 is provided with an inwardly extending friction fin or plate 68 facing the fin 65 on the rear plate and is secured at its upper end to the beam 66 and at its low end to the lower beam 67 by a plurality of bolts and plates 69 so as to facilitate the assembling or removal of the pawl carriage and the parts associated with it. The housing plates should be made of stainless steel so that their coefficient of friction will remain constant before and after the safety has been in salt water spray. The pawl carriage 64 is a long channel-like, stainless steel block disposed in a recess 70 formed by the outer left-hand edges of the housing plates and their friction fins (Fig. 9). It is shorter than the housing plates and they may slide up or down on it in case of a safety stop. Three up pointing pawls 71, 72 and 73 and three down pointing pawls 74, 75, and 76 are mounted in the carriage body for engaging safety standards such as the notched portions 33 of the guide rail to stop the pawl carriage when the cables fail.

The base of the down pointing pawl 76 is rotatably seated in a socket 77 in the carriage body and is retained in that position by a loose hinge pin 77a.

A compression spring 80 is provided for biasing the pawl 76 to project outwardly. The spring 80 is concentrically mounted on a rod 81 having its inner end pivotally attached to the pawl 76 by a pivot pin 82 and is compressed between a shoulder 83 on the lower end of the rod 81 and a spanner nut 84 mounted on the outer end of a tube 85, the inner end of which is seated in and welded to the pawl carriage 64. Each pawl is provided with a finger projection 78 at its one side to be engaged by a holding gate 79 controlled by the operating rod 56 so that operation of the rod will open the gate to release the pawls to engage the notches 60 in the guide rails upon failure of one or both sets of cables.

A temporary nut 86 is illustrated as mounted on the screw threaded end of the rod 81 for holding the pawl 76 within its recess until the gate 79 is closed to hold the pawl. After the resetting operation of closing the gate, the nut 86 is removed and the gate holds the pawl against the effect of the biasing spring 80. Each of the pawls is provided with a similar biasing spring. The pawl carriage 64 is shorter than the recess formed by the housing plates in which it is disposed so that it may move longitudinally a limited distance therein either direction when the safety is set to stop the platform.

In order to provide a predetermined frictional resistance to the movement of the carriage in the housing plates, a strip of brake lining 83 is fastened to the carriage 64 in position to engage the adjacent face of the friction fin 65 and a strip of brake lining 89 is fastened to the carriage body in position to engage the adjacent face of the friction fin 68. A friction plate 90 is disposed at the other sides of the fins 65 and 68 and is loosely mounted upon a plurality of short round tubular projections 91 mounted in the central inner face of the pawl carriage and welded thereto to make a solid connection therewith so that vertical movement of the carriage will carry the friction plate 90 with it. The friction plate 90 is also provided with holes which permit it to fit over the tubular supports 85.

A strip of brake lining 92 is mounted on the friction plate 90 in position to engage the adjacent face of the friction fin 68 (Fig. 9) and a similar strip 93 of brake lining is disposed on the opposite side of the friction plate to engage a "long" friction bar 94 embraced between that brake lining and a strip of brake lining 95 mounted on a friction strip 96. A strip of brake lining 97 is fixed on the friction plate 90 in position to engage the adjacent face of the friction fin 65 and a strip of brake lining 98 is fixed on the opposite side of the friction plate 90 in position to engage a "short" friction bar 99 disposed between that strip of brake lining and a strip of brake lining 100 fastened to the friction strip 96. The lower ends of the bars 94 and 99 sit on the bottom plate 101 resting on and welded to the beam 67.

The friction strip 96 is loosely mounted upon the tubular members 85 so that it as well as the friction plate 90 will remain with the pawl carriage when the pawl carriage is stopped by the safety pawls and the continued motion of the platform moves the housing plates up or down on the carriage. This arrangement of the pawl carriage, the friction fins, plate, bars and strip with the brake lining strips disposed therebetween provides a frictional resistance to brake the movement of the housing plates on the pawl carriage when it grips the guide rails for absorbing the shock of suddenly stopping the platform by the setting of the safety pawls.

A plurality of heavy friction springs are provided for pressing the friction plates, rods, fins, and the carriage body tightly together to increase their frictional resistance to a predetermined amount sufficient to bring the platform to rest within a predetermined distance after the safety pawls set on the guide rails. The heavy friction springs associated with the pawl 76 bear the reference characters 106 and 107 and are concentrically mounted on the tubular support 85 between the outer face of the friction strip 96 and a round shoulder plate 108 mounted on the outer end of the tubular support 85 and held in position thereon by the spanner nut 84.

A lock washer 109 and a lock washer base 110 are mounted between the spanner nut and the shoulder plate 108 to prevent the spanner nut 84 from getting loose after it is tightened on its friction spring. The lock washer base is provided with a pin 111 which extends into a depression in the shoulder plate and the lock washer is provided with a serrated edge, one of the projections 112 of which is bent downwardly into a depression in the lock support and another projection 113 of which is bent upwardly into a notch in the spanning nut after the spanning nut is tightened against the shoulder plate 108. The compression springs 106 and 107 are very strong and it is usual to use a lever arrangement for turning the spanner nut 84 down against the springs to compress them sufficiently against the friction strip 96. Similar compression springs are mounted in a similar manner opposite each pawl. The compression springs are so designed that they cover practically the whole area of the compression strip. Hence the pressure on the brake linings will be very evenly distributed.

The holding gate 79 (Fig. 6) is a rectangular framework constructed of seamless steel tubing 115 welded together with its rear end pivotally mounted at the points 116 and 117 on the safety support beams 66 and 67. The front edge tube 75 118 of the gate has welded to it a rectangular

facing strip 119 (Fig. 9) which bears against the fingers 78 on the pawls and holds the pawls within their recesses as long as the gate is in its closed position. When the gate is released, the pawls fly outwardly under the force of their compression springs 106 and 107 into engagement with the notches 33 in the guide rails to stop the safety.

The down pawls in the drawings are located a distance apart approximately equal to one and two-thirds of the pitch of the notches 33 in the guide rail so that the setting of the pawls against the notches will stop the safety instantly or at the most, where the pitch of the notches is, say, six inches, within a two inch travel of the safety along the rail after failure of one or both sets of cables. The up pawls are also shown in the drawings as located a distance apart equal to one and two-thirds of the pitch of the notches 33 in the guide rail so that the setting of the up pawls against the notches will stop the safety instantly or at the most within a two inch up travel of the safety along the rail after cable failure. In other words, the pawls are fractionally spaced apart with respect to the pitch of the notches to permit only a fractional pitch of free fall regardless of when the safety sets.

The means for holding the gate 79 in its closed position to prevent operation of the pawls while the cables remain intact comprises (Fig. 5) a holding rod 120 having its one end pivotally connected to the gate and its other end pivotally connected to the outer end of a lever arm 121 fixed on the operating rod 55. When the operating rod is rotated to cause operation of the safeties, the arm moves the rod 120 axially to the right and thereby moves the gate away from the fingers on the pawls, thus releasing the pawls.

The operating rod 55 is a long rotatable shaft extending the full length of the platform and supported in a plurality of bearings 122 on the platform. The rod is made up of a plurality of sections with spline points at every bearing securing it to the platform so that it may be rotated freely and easily in the event of failure of the cables without any trouble due to warping or weaving of the platform frame 23.

The safety 54 at the fore end of the platform is constructed in the same manner as the safety 53 at the aft end of the platform and its gate 124 is connected by a rod 125 and a lever arm 126 to the operating rod 55 in the same manner as the gate 53 is connected thereto so that operation of the rod 55 at any time will effect simultaneous operation of the pawl freeing gates on both safeties 53 and 54.

The casing 57 for the biasing spring 56 is mounted on the central portion of the frame 23 adjacent to the center portion of the operating rod 55. The spring 56 is mounted between the bottom of the casing 57 and a push rod 127, the outer end of which extends out of the casing and is pivotally connected by a hinge joint 128 to the outer end of a lever arm 129 fixed on the operating rod 55 so that the spring 56 tends to rotate the rod 55 to open the pawl gates and release the pawls into the notches in the guide rails.

The means for restraining the rod against rotation by the biasing spring 56 comprises a safety cable 131 extending the full length of the platform with its ends connected by triggers 135 and 135a with the trigger plates and its central portion is threaded through a thimble device 132 on the outer end of the arm 129 opposite the spring push rod 127. The aft end of the safety cable 75

is threaded through an eyelet bearing 133 in the frame 23, over a slide bearing 134 on the frame and down to the rear end of the trigger 135 pivotally mounted in a bearing 136 on the underside of the cable hitch bracket 42a. The front end of the trigger 135 is provided with a trigger face resting on a trigger point 137 welded to the trigger plate 58.

The trigger plate 58 rests loosely against the lower face of the cable hitch box 139 which is constructed of a plurality of metal plates welded together and to the hitch bracket in a box-like construction. Each of the cables 16 is pivotally connected by a socket 140 to the upper end of a hitch rod 141, the lower end of which passes through the hitch box 139 and the trigger plate 58 and is secured in that position by a plurality of nuts 142.

A compression spring 143 is mounted on each 20 hitch rod and is compressed between the inner face of the top plate on the hitch box and the upper face of the trigger plate. When the cables and the trigger plate are installed, the nuts 142 are turned to draw the hitch rods to the point 25 where the trigger plate engages the underside of the hitch box and thereby compresses the springs 143 until the trigger plate provides a dead end hitch for the cables and the springs store up sufficient energy to throw the trigger plate downwardly upon failure of the cables. It will be obvious that the springs 143 should be of such size that they will be strong enough to kick out the trigger plate 58 upon failure of the cables but will not be strong enough to raise the hitch box 35 above the trigger plate.

The fore end of the safety cable (Fig. 3) extends through an eyelet bearing 145 in the frame 23 and then down over a slide shoe 146 to the rear end of the trigger 135a mounted on the bracket for the cable hitch 48 in association with the trigger plate 59 as its aft end is connected with the trigger and trigger plate at the cable hitch 42.

With this arrangement of the safety cable, the failure of either set of cables will release its trigger plate which, in turn, will release its trigger and thereby release the safety cable to release the arm 129 of the rotating rod 55 and thereby permit that rod to turn in its bearings under the biasing operation of the spring 56 and thus move the crank arms 121 and 126 to operate their rods 120 and 125 to open the gates 79 and 124 at the ends of the platform, thus releasing all of the pawls simultaneously on both of the safeties 53 and 54 to stop the safeties on the notched guide rails.

A slipper or bumper block 148 (Fig. 11) is mounted in the outer end of each of the beam supports 66 and 67 in position to engage a plate at the side of the guide rail when the platform may be moved endways an excessive distance under excessive wave shock.

As illustrated in Fig. 10, a resetting and holding bolt 150 is mounted in vertical position in the upper support beam 66 to pass down through that beam and through the upper end of the pawl carriage 64. The bolt is provided with suitable nuts by means of which the pawl carriage 64 may be reset to its correct position in approximately the center of the safety housing after it has been moved downwardly under the impact of a safety operation and also acts as an initial resistance to up movement of the platform on the carriage during a safety stop. The bolt 150 has a cut away portion 150a to a small diameter to insure

its failure under a predetermined strain when its end of the platform is in an up safety stop. Thus the bolts 150 provide an initial predetermined resistance to upward movement of either end of the platform before the increased frictional resistance comes into play in an up safety stop or up tilting of either end of the platform.

In the prior art the practice has been to endeavor to equalize the braking effect of a safety device between a plurality of rails with the intention of keeping the platform level when it comes to rest.

In a deck-edge elevator the platform is so large, sometimes sixty feet long and over thirty feet wide, that distortion is almost inevitable; also the unequal positioning of load is expected and allowable. Therefore, the present safety is designed to permit the platform to stop at a predetermined maximum amount out of level, governed by the spacing or the distance between the notches for the pawls, the staggering of the pawls in relation thereto on the sides of rails and the housing dead stop when it has passed through its maximum cushioning space between the carriage and the ends of the housing 61. The elevator in battle action will be able to run on only one cable on each side of platform should the other cables be shot away. The safeties will be set only when all the cables on one side or the other fail, and the safeties for both rails will be set when all the cables on either side fail.

Assumed operation of the apparatus

It will be assumed that the safety apparatus has been placed in condition for operation; that is, all the compression springs 106 and 107 have been compressed against the friction strip 96 by rotating the spanner nuts 84 to the necessary degree; that the pawl restraining gates 79 and 124 have been pulled up against the restraining fingers 78 on the pawls, and are held in that position by reason of the fact that the triggers 135 and 135a have been placed behind the trigger points 137 on the trigger plates 58 and 59; and that all of the temporary nuts 86 on the pawl rods 81 have been removed to permit the pawl springs 80 to bias the pawls outwardly against their restraining gates.

It will be assumed now that the elevator platform has been loaded and is being moved from its upper deck to its lower deck by the usual operation of the hoisting engine 18 to lower the platform.

It will be assumed further that the cables 16 fail by reason of being shot away or suddenly breaking and thereby permit the platform to fall unless the safety apparatus operates to stop it and support it on the guide rails.

The complete failure of the hoisting cables 16 permits the stored up energy in the trigger springs 143 (Fig. 6) to "shoot" the trigger plate 58 away from the hitch base 139 and thereby release the trigger 135 to effect the release of the stopping pawls and cause the platform to be stopped and brought to rest on the guide rails.

The release of the trigger 135 causes its rear arm to fly upwardly under the tension in the safety rope 131 and thereby release the tension rope from holding the operating rod arm 129 against the pressure exerted by the biasing spring 56 in the casing 57. Upon being released, the biasing spring 56 pushes its biasing rod 127 (Fig. 7) outwardly against the operating rod arm 29 and rotates that arm in clockwise direction (Fig. 5) and thereby rotates the operating rod 55. This

rotation of the operating rod moves its lever arms 121 and 126 in clockwise direction (Figs. 3, 4 and 5) simultaneously to operate their rods 120 and 125 to push the gates 79 and 124 open simultaneously thus releasing the pawls into engagement with the notches in the guide rails.

The outward movement of the gate 79 moves its outer edge 119 away from the pawl fingers 78 on the safety 53, thereby releasing the pawls to the effect of their biasing springs 80. In considering Fig. 5, it will be assumed that the down pawl 76 projects into the notch shoulder 33a and thereby stops the pawl carriage 64 on the guide rail.

Inasmuch as the elevator platform 19 weighs many tons, its down movement will suddenly throw an enormous load upon the carriage, but the frictional resistance between the fins on the housing and long rods held by the housing plates and the friction plate and strip held by the carriage due to the brake linings mounted between them will cushion the down movement of the platform and housing against the stopped carriage sufficiently to bring the aft end of the elevator platform to rest on the pawl carriage without doing any damage to the elevator structure.

It should be noted that the short friction rod is not effective in this operation. This occurs because the short friction rod does not extend to the upper end of the housing and, therefore, is not moved downwardly between the adjacent brake linings.

Inasmuch as the gate 124 for the safety 54 was opened simultaneously with the gate 79 on the safety 53, the pawl carriage on the safety 54 will be operated simultaneously to grip the guide rail 12 and bring the fore end of the elevator to rest in the same manner as the aft end was brought to rest.

If both sets of cables break at the same time while the platform is being lowered, the safeties will be operated in the same manner.

It will be assumed now that the hoisting cables 16 are repaired and that the housing engine is operated to raise the platform slightly to release the pawls from the notches in the guide rails. First the spanner nuts 84 are loosened to free the friction plates so that the carriage can be restored to its control location at approximately the center of the recess 70 in which it is disposed, where it will be in its correct position for the next safety operation. Next the temporary nuts 86 are placed on the pawl rods 81 and tightened to pull the pawls within their recesses. After the pawls are pulled in, the carriage is moved to its central position and the spanner nuts are tightened. Next the gates 79 and 124 are reclosed against the restraining fingers 78 on the pawls and the safety rope 131 is again adjusted on the triggers 135 and 135a so as to return the biasing spring 56 to its compressed biasing position in its casing 57. After the gates 79 and 124 are returned to their pawl restraining positions and are held in such positions by the safety rope 131 fastened to the triggers, which are in turn held by the trigger plates 58 and 59, the temporary nuts 86 are removed and the safety is ready for operation again when needed.

It will be assumed now that the elevator has been in operation for some time, and that while it is being moved upwardly from the lower deck to the flight deck, its hoisting cables 17 on the fore end of the elevator are shot away and that that end of the platform starts to fall. Meanwhile the hoisting engine is raising the aft end 75 of the elevator platform through the cables 16.

When the fore end of the platform started to fall, the broken cables 17 permitted the trigger plate 59 to move downwardly under its energy storing springs and thus released the trigger 135a to release the safety cable 131. The release of the cable 131 releases the biasing spring 56 so that it rotates the operating rod 55 as described in the previous safety operation, and it, in turn, simultaneously opens both gates 79 and 124. The release of the gate 124 sets the pawl carriage of the safety 54 to be stopped by its down pawls engaging the notched guide rail 12 and the fore end of the platform is brought to rest on the pawl carriage in the same manner as in the previously described operation.

However, in this accident the hoisting engine is raising the platform and the intact cables 16 continue to exert an upward force on the aft end of the platform tending to tilt the platform dangerously. This tilting tendency is quickly stopped because the pawls of the safety 53 are released to engage the notched guide rail 11. In this instance it will be assumed that the up pawl 73 engages the notched shoulder 335 and thereby stops any further upward movement of its pawl carriage. Inasmuch as the pawl carriage is now prevented from moving upwardly any further, the aft end of the platform will be stopped from any further upward movement and the energy involved in this stopping effect will be absorbed by the failure of the bolt 150 and by the frictional resistance between the plates carried by the pawl carriage and the fins carried by the housing plates as well as by the long friction rod and the short friction rod mounted to rest on the bottom of the housing.

Inasmuch as the short friction rod is effectively used in this operation, the total frictional resistance is greater than the frictional resistance effective in a down stop. This increased frictional resistance in an up safety stop is sufficient to take care of the up pull exerted by the hoisting engine on the cables 16 so that the platform is stopped without becoming dangerously tilted upwardly at the end to which the intact cables are attached.

It will be assumed now that the cables are repaired and that the safety apparatus is restored to its normal condition for the next safety action in the same manner as described in the previous assumed actions.

By the foregoing description it will be seen that we have provided an improved safety apparatus for elevators which is particularly useful in connection with extremely large and long hoistable bodies such as airplane elevator platforms, drawbridges, extremely heavy freight elevators, etc. It will also be observed that the safety apparatus will stop the platform when either one or both sets of cables fail during down travel of the platform, or when both sets of cables fail during up travel, and that it will stop one end of the platform when it starts to fall during up operation and the other end of the platform if it starts to tilt upwardly under the up pull of the cables on that end.

Furthermore, if the safety is used on an elevator having a set of hoisting cables at each end, the safety will operate simultaneously at both ends for either direction of travel regardless of whether either one of the sets of cables breaks or both sets of the cables break. It will also be observed that the safety will provide different degrees of stopping friction for the up and the down directions to take care of the difference in force

exerted by the platform being pulled up at one end and the force exerted by the down falling end.

Although we have illustrated and described only one embodiment of our invention, it is to be understood that changes therein and modifications thereof may be made without departing from the spirit and scope of the invention.

We claim as our invention:

1. In an elevator, a platform, a hoisting means for each end of the platform, an engine for operating the hoisting means to raise or lower the platform, a pair of guide rails for guiding the platform, each of said guide rails being provided with a notched surface, a safety device for each end of the platform adjacent to the guide rails, a frictional means connecting each safety device to its end of the platform to permit frictionally resisted movement of the platform on the safety device, means mounted with said frictional means for providing greater frictional resistance to an up safety stop of the platform than to a down safety stop of the platform, a plurality of up safety pawls mounted in each of said safety devices in position for engaging its notched guide rail, said up pawls being fractionally spaced apart with respect to the pitch of the notches in its guide rail, a plurality of down safety pawls mounted in each of said safety devices in position for engaging its notched guide rail, said down pawls being fractionally spaced apart with respect to the pitch of the notches in its guide rail, resilient means for biasing said pawls into locking engagement with the notched portions of the guide rails, a gate associated with each of said safety devices for restraining the safety pawls thereon from engagement with the guide rail associated therewith, an operating rod connected to both of said gates, a biasing means for biasing said operating rod to move said gates to pawl releasing position, a safety cable connected to said operating rod to restrain it from moving the gates to their pawl-releasing positions, a hitch device for connecting each hoisting means to its end of the platform, a trigger attached to each end of the safety cable and pivotally mounted adjacent a hitch device, a trigger plate associated with each hitch device for restraining operation of the trigger adjacent thereto and, an energy storing device mounted on each hitch device and responsive to the tension of the hoisting means attached thereto for storing energy to move the trigger plate associated with that hitch box upon failure of that hoisting means to thereby release its trigger on the safety cable and thereby cause the setting of the pawls on both safety devices in the notched portions of the guide rails to stop the platform.

2. In an elevator, a platform, a hoisting means for each end of the platform, an engine for operating the hoisting means to raise or lower the platform, a pair of guide rails for guiding the platform, each of said guide rails being provided with a notched surface, a safety device for each end of the platform adjacent to the guide rails, a frictional means connecting each safety device to its end of the platform to permit frictionally resisted movement of the platform on the safety device, means mounted with said frictional means for providing greater frictional resistance to an up safety stop of the platform than to a down safety stop of the platform, a plurality of up safety pawls mounted in each of said safety devices in position for engaging its notched guide rail, said up pawls being fractionally spaced apart with respect to the pitch of the notches in its guide

rail, a plurality of down safety pawls mounted in each of said safety devices in position for engaging its notched guide rail, said down pawls being fractionally spaced apart with respect to the pitch of the notches in its guide rail, resilient means for biasing said pawls into locking engagement with the notched portions of the guide rails, a gate associated with each of said safety devices for restraining the safety pawls thereon from engagement with the guide rail associated therewith, an operating rod connected to both of said gates, a safety cable connected to said operating rod to restrain it from releasing the gates to their pawl releasing positions, a hitch device for connecting each hoisting means to its end of the platform, a trigger means connecting each end of the safety cable to a hitch device, an energy storing device mounted on each hitch device and responsive to the tension of the hoisting means attached thereto for storing energy to operate the trigger means associated with that hitch box upon failure of that hoisting means for releasing the safety cable and thereby causing the setting of the pawls on both safeties in the notched portions of the guide rails to stop the platform.

3. In an elevator, a platform, a set of hoisting cables for each end of the platform, an engine for operating the cables to raise or lower the platform, a pair of guide rails for guiding the platform, each of said guide rails being provided with a notched surface, a safety device for each end of the platform adjacent to the guide rails, a frictional means connecting each safety device to its end of the platform to permit frictionally resisted movement of the platform on the safety device, means mounted with said frictional means for providing greater frictional resistance to an up safety stop of the platform than to a down safety stop of the platform, a plurality of up safety pawls mounted in each of said safety devices in position for engaging its notched guide rail, said up pawls being fractionally spaced apart with respect to the notches in its guide rail, a plurality of down safety pawls mounted in each of said safety devices in position for engaging its notched guide rail, said down pawls being fractionally spaced apart with respect to the notches in its guide rail, resilient means for biasing said pawls into locking engagement with the notched portions of the guide rails, and means responsive to intact condition of the both sets of cables for restraining the safety pawls from engaging the guide rails and responsive to failure of either set of cables for releasing the pawls into engagement with the guide rails for stopping the platform.

4. In an elevator, a platform, a hoisting means for each end of the platform, an engine for operating the hoisting means to raise or lower the platform, a pair of guide rails for guiding the platform between floors, each of said guide rails being provided with a notched surface, a safety device mounted at each end of the platform adjacent to the guide rails, a plurality of up safety pawls mounted in each of said safeties, a plurality of down safety pawls mounted in each of said safeties, resilient means for biasing said pawls toward locking engagement with the notched portions of the guide rails, a gate associated with each of said safeties for restraining the safety pawls thereon from engagement with the guide rail associated therewith, a plurality of levers connected to said safety gates, an operating rod connected to said levers, a biasing means for biasing said operating rod to move said levers and said gates to pawl-releasing posi-

tion, a safety cable for restraining the operating rod from moving the gates to their pawl releasing positions, a hitch device for connecting each hoisting means to the platform, a trigger attached to each end of the safety cable and pivotally mounted adjacent a hitch device, a trigger plate associated with each hitch device for restraining operation of the trigger adjacent thereto, and an energy storing device mounted on each hitch device and responsive to the tension of the hoisting means attached thereto for storing energy to move the trigger plate associated with that hitch box upon failure of that hoisting means, to release its trigger on the safety cable and thereby cause the setting of the pawls on both safeties in the notched portions of the guide rails to stop the platform.

5. In an elevator, a movable platform, a hoisting means for each end of the platform, an engine for operating the hoisting means to raise or lower the platform, a safety element fixed adjacent to each end of the platform, a safety device mounted on each end of the platform adjacent to the safety element at that end of the platform, a plurality of safety pawls mounted in said safeties, resilient means for biasing said pawls toward locking engagement with the safety elements, a gate associated with each of said safeties for restraining the safety pawls thereon from engagement with the safety element associated therewith, an operating rod connected to said safety gates, a biasing means for biasing said operating rod to move said gates to pawl-releasing position, a safety cable for restraining the operating rod from moving the gates to their pawl releasing positions, a hitch device for connecting each hoisting means to the platform, a trigger attached to each end of the safety cable and pivotally mounted adjacent a hitch device, a trigger plate associated with each hitch device for restraining operation of the trigger adjacent thereto and, an energy storing device mounted on each hitch device and responsive to the tension of the hoisting means attached thereto for storing energy to move the trigger plate associated with that hitch box upon failure of that hoisting means to release its trigger on the safety cable and thereby cause the setting of the pawls on both safeties in the notched portions of the guide rails to stop the platform.

6. In an elevator, a movable platform, a hoisting means for each end of the platform, an engine for operating the hoisting means to raise or lower the platform, a pair of guide rails for guiding the platform between floors, each of said guide rails being provided with a notched surface, a safety device mounted at each end of the platform adjacent to the guide rails, a plurality of safety pawls mounted in said safeties, resilient means for biasing said pawls toward locking engagement with the notched portions of the guide rails, a gate associated with each of said safeties for restraining the safety pawls thereon from engagement with the guide rail associated therewith under the pressure of their biasing means, an operating rod connected to said gates, a biasing means for biasing said operating rod to move said gates to pawl-releasing position, a safety cable for restraining the operating rod from moving the gates to their pawl-releasing positions, and means responsive to the failure of either hoisting means for releasing the safety cable and thereby causing the setting of the pawls on both safeties in the notched portions of the guide rails to stop the platform.

7. In an elevator, a movable platform, a hoist-

ing means for each end of the platform, an engine for operating the hoisting means to raise or lower the platform, a safety standard fixed adjacent to each end of the platform, a safety mounted on each end of the platform adjacent to the safety standard thereat, a plurality of up safety pawls mounted in each of said safeties for engaging its safety standard to prevent up movement of the platform, a plurality of down safety pawls mounted in each of said safeties, for engaging its safety standard to prevent down movement of the platform, means for biasing said pawls toward locking engagement with the safety standards, means associated with each of said safeties for restraining the safety pawls thereon from engagement with the safety standard associated therewith, hitch devices for connecting the hoisting means to the platform, and trigger means associated with the hitch devices and responsive to intact condition of the hoisting means for preventing the pawl restraining means from releasing the pawls and responsive to failure of the hoisting means at either end of the platform for causing the pawl restraining means to release the pawls into locking engagement with the safety standards to stop the platform in either direction.

8. In an elevating apparatus, a movable platform, hoisting cables for the platform a safety standard provided with notches disposed adjacent the platform, a safety device mounted on the platform, a plurality of up safety pawls pivotally mounted in the safety device for engaging the notches in the safety standard, said up pawls being fractionally spaced apart with respect to the pitch of the notches in the safety standard, a plurality of down safety pawls pivotally mounted in the safety device for engaging the notches in the safety standard, said down pawls being fractionally spaced apart with respect to the pitch of the notches on the safety standard, means for biasing the pawls toward engagement with the notches in the safety standard, and means responsive to intact condition of the hoisting cables for preventing the pawls from engaging the safety standards and responsive to failure of the hoisting cables for releasing the pawls into engagement with the safety standard to stop the platform.

9. In an elevator, a movable platform, a set of hoisting cables for each end of the platform, a safety standard provided with notches disposed adjacent to each end of the platform, a safety device mounted on each end of the platform, a plurality of up safety pawls pivotally mounted in each safety device for engaging the notches in its safety standard, said up pawls being fractionally spaced apart with respect to the pitch of the notches in the safety standard, a plurality of down safety pawls pivotally mounted in each safety device for engaging the notches in its safety standard, said down pawls being fractionally spaced apart with respect to the notches on its safety standard, means for biasing the pawls toward engagement with the notches in the safety standards, and means responsive to intact condition of both sets of hoisting cables for preventing the pawls from engaging the safety standards and responsive to failure of either set of hoisting cables for releasing all the pawls into engagement with the safety standard to stop the platform.

10. In an elevating apparatus, a movable platform, hoisting cables for the platform, a safety standard provided with notches disposed adjacent

the platform, a safety device, means for mounting the safety device on the platform, a plurality of up safety pawls pivotally mounted in the safety device for engaging the notches in the safety standard, said up pawls being fractionally spaced apart with respect to the notches in the safety standard, a plurality of down safety pawls pivotally mounted in the safety device for engaging the notches in the safety standard, said down pawls being fractionally spaced apart with respect to the notches on the safety standard, means for biasing the pawls toward engagement with the notches in the safety standard, means responsive to intact condition of the hoisting cables for preventing the pawls from engaging the safety standard and responsive to failure of the hoisting cables for releasing the pawls into engagement with the safety standard to stop the platform, and slidable friction means disposed in the safety mounting means for providing frictional resistance to movement of the platform on the safety device when it engages the safety standard in making a safety stop of the platform.

11. In an elevator, a platform, a housing attached to the platform, a friction plate carried by the housing, a carriage, a pawl mounted on the carriage for engaging a safety element during a safety stop, a friction plate carried by the carriage, and adjustable resilient means for mounting the carriage on the housing by holding the plates in slidable frictional engagement with each other, means for limiting the relative movement of the plates, and an adjusting device mounted on the housing and the carriage for returning the carriage to its predetermined normal position on the housing after it has been dislodged therefrom in a safety operation.

12. In an elevator, a safety element, a platform movable along the safety element, a housing attached to the platform, a friction plate carried by the housing, a carriage, a pawl mounted on the carriage for engaging the safety element during a safety stop, a friction plate carried by the carriage, and means for mounting the carriage on the housing by holding the plates in slidable frictional engagement with each other, to permit relative movement between the platform and the carriage when the pawl engages the safety element.

13. In an elevator, a platform, a housing attached to the platform, a friction plate carried by the housing, a carriage, a pawl mounted on the carriage for engaging a safety element during a safety stop, a friction plate carried by the carriage, an adjustable resilient means for mounting the carriage on the housing by holding the plates in slidable frictional engagement with each other, and means for limiting the relative movement of the plates.

14. In a safety device for an elevating means, a movable platform, hoisting cables for the platform, a safety standard associated with the platform, a housing mounted on the platform, a safety device for engaging the standard to stop the platform, a friction plate carried by the safety device, means for frictionally attaching the safety device friction plate to the housing friction plate to permit one to slide on the other and thereby create frictional resistance to relative movement of the safety device and the housing and means controlled by the cables for preventing the safety device from grabbing the safety standard while the cables are intact and for causing the safety

device to grab the safety standard and stop the platform upon failure of the cables.

15. In a safety device for an elevating means, a movable platform, a set of hoisting cables for each end of the platform, a safety standard associated with each end of the platform, a housing mounted on each end of the platform, a friction plate mounted on each housing, a safety device for the housing at each end of the platform for engaging the standard at that end of the platform to stop the platform, a friction plate carried by each safety device, means for frictionally attaching the friction plate of each safety to the friction plate on its housing to permit them to slide on each other and thereby create frictional resistance to relative movement of the safety devices and the housings, means controlled by both sets of cables for preventing the safety devices from grabbing the safety standards while both sets of cables are intact and for causing both safety devices to grab the safety standards and stop the platform upon failure of either set of cables.

16. In a safety device for an elevating means, a movable platform, hoisting cables for the platform, a safety standard associated with the platform, a housing mounted on the platform, a friction plate mounted on the housing, a safety device for engaging the standard to stop the platform, a friction plate carried by the safety device, means for frictionally attaching the safety device friction plate to the housing friction plate to permit one to slide on the other and thereby create frictional resistance to relative movement of the safety device and the housing, additional frictional means disposed in the frictional attaching means to provide greater frictional resistance to upward movement of the housing on the safety device than to downward movement of the housing on the safety device, means controlled by the cables for preventing the safety device from grabbing the safety standard while the cables are intact and for causing the safety device to grab the safety standard and stop the platform upon failure of the cables.

17. In an elevating device, a movable platform, hoisting cables for the platform, a housing mounted on the platform, a safety device associated with the housing for stopping the platform upon failure of the cables, and friction means for mounting the safety in the housing, said friction means comprising, a friction plate mounted in the housing, a plurality of tubes having their inner ends fixed in the safety device, a friction plate mounted on the tubes and disposed in slidable contact with the plate in the housing, a plurality of springs mounted on the outer ends of the tubes, and means for compressing the springs against the plates to secure a predetermined frictional resistance between the plates for braking the movement of the housing on the safety device.

18. In an elevator, a movable platform, a fixed safety element disposed adjacent to the platform, a housing attached to the platform, a long friction rod disposed in the housing with its upper end and its lower end extending approximately into engagement with the ends of the housing, a short friction rod disposed in the housing with its lower end in approximate engagement with the lower end of the housing and its upper end some distance from the upper end of the housing whereby it will be moved upwardly by the housing when the housing moves upwardly on the carriage but not downwardly when the housing

moves downwardly on the carriage, a carriage slidably disposed in the housing, a pawl mounted on the carriage for engaging a safety element during a safety stop, a friction plate carried by the carriage, and means for mounting the carriage on the housing by holding the plates and rods in slidable frictional engagement with each other, whereby the frictional resistance created by upward movement of the housing on the carriage is greater than the frictional resistance created by downward movement of the housing on the carriage.

19. In a safety mechanism for an elevator, a movable platform, a set of hoisting cables at each end of the platform, a safety standard associated with each end of the platform, a housing mounted on each end of the platform, a frictional plate mounted on each housing, a safety device disposed at each end of the platform for engaging the standard thereto to stop the platform, a friction plate carried by each safety device, means for frictionally attaching the friction plate of each safety device to the friction plate of the housing device at its end of the platform to create frictional resistance to relative movement of the housings and the safety devices, a bolt connecting the upper end of each housing to the upper end of the safety device associated with it, said bolt having a predetermined failure value when subjected to a tension strain to prevent upward movement of the housing relative to the safety device whereby an upward movement of one end of the platform in a safety stop will be initially restrained by the predetermined strength of the bolt and after the failure of the bolt will be frictionally restrained by the action of the friction plates, and means controlled by both sets of cables for preventing the safety devices from grabbing the safety standards while the cables are intact and for causing the safety devices to grab the safety standards for stopping the platform upon failure of either set of cables.

20. In a safety mechanism for an elevator, a movable platform, a set of hoisting cables for the platform, a safety standard associated with the platform, a housing mounted on the platform, a safety device mounted on the housing with a limited degree of movement therebetween, means controlled by the cables for preventing the safety device from grabbing the safety standard while the cables are intact and for causing the safety device to grab the safety standard for stopping the platform upon failure of the cables, a holding means connecting the housing and the safety device, said holding means being constructed to fail when it is subjected to a predetermined strain for initially preventing movement of the housing relative to the safety device in a safety stop until the force exerted by the housing reaches a predetermined value, and frictional means disposed between the housing and the safety device for cushioning the stopping of the housing on the safety device in the event of failure of the holding means during a safety stop, whereby the housing will be first prevented from movement on the safety device by the holding means during a safety stop and upon failure of the holding means will be frictionally restrained by the friction means.

21. In a safety mechanism for an elevator, a movable platform, a set of hoisting cables for each end of the platform, a safety standard associated with each end of the platform, a housing mounted on each end of the platform, a safety device associated with each housing for engaging the

standard thereat to stop the platform, means controlled by the cables for preventing the safety device from grabbing the safety standards while both sets of cables are intact and for causing the safety devices to grab the safety standards when either set of cables fails for the purpose of stopping the platform upon the failure of either set of the cables, frictional means of a predetermined value disposed between each housing and its safety device for cushioning the stopping of the platform on that safety device in the down direction

10

by a down setting of the safety devices, and additional frictional means disposed between each housing and its safety device for operating in conjunction with the first-named frictional means to provide friction of a greater predetermined value for cushioning the stopping of the platform on that safety device in the up direction by an up setting of the safety device.
